UNITED STATES PATENT OFFICE.

ALBERT J. BATES, OF JOLIET, ILLINOIS, ASSIGNOR TO THE JOLIET BARB WIRE COMPANY, OF SAME PLACE.

WIRE-BARBING MACHINE.

SPECIFICATION forming part of Letters Patent No. 325,311, dated September 1, 1885.

Application filed July 6, 1885. (No model.)

To all whom it may concern:

Be it known that I, ALBERT J. BATES, a citizen of the United States of America, residing at Joliet, in the county of Will and State 5 of Illinois, have invented certain new and useful Improvements in Wire-Barbing Machines, of which the following is a specification, reference being had therein to the accompanying drawings.

10 Figure 1 is a plan view of the top of the machine. Fig. 2 is a vertical cross-sectional view of the machine on line 2 of Fig. 1, looking in the direction of the arrow. Fig. 3 is a detail perspective view of the several barb-cutters and formers and guides, showing their 15 position and relation to each other. Fig. 4 is a perspective view of a section of the barb-strip as it would appear when a barb has been cut and formed and a prod cut and formed—one on each of the two next succeeding bars. Fig. 5 is a side view of the reciprocating strand-wire guide, showing it mounted on one of the barb-cutters on which it reciprocates, looking in the direction of arrow 2 of Fig. 3. 20 Fig. 6 is a side view of the ratchet mechanism for operating the barb-strip feed-rolls; and Fig. 7 is a perspective view of a four-pointed flat metal barb seated between a pair of cabled strand-wires, it being the product of the 25 machine.

30 This invention relates to certain improvements in a machine for cutting, forming, and setting four-pointed flat metal barbs between a pair of strand-wires afterward cabled together to hold them in place, and is designed to be certain improvements on the machine for said purpose for which Letters Patent of the United States were on the 19th day of May A. D., 1885, granted to me and numbered 318,079, which improvements consist, 35 principally, in the parts that operate the barb-cutters, and in a reciprocating strand-wire guide, and which improvements are fully set forth and explained in the following specification and claims.

40 Referring to the drawings, B represents the main bed-frame of the machine mounted on suitable legs, and upon which bed the working parts of the machine are properly arranged 45 and supported.

B' represents a secondary and elevated bed mounted on bed B, and arranged to support the stationary barb-cutters d, d', and h, barb-strip guides n and k, stationary strand-wire guide t, and reciprocating strand-wire guide 55 E, in the manner represented in Figs. 1 and 2, and located with reference to each other as shown in Fig. 3.

S represents the drive-shaft of the machine, located in suitable boxes across the top of bed 60 B, near one end of the machine, and arranged to support cam c, crank-wheel Z, and large spur gear-wheel D, all rigidly secured thereto and located as shown in Fig. 1, and adapted to receive motion by means of said spur-gear 65 meshing with a corresponding but smaller gear-wheel, A, secured to a twister-yoke, (shown at T, Fig. 1.) As the twister and spooler is no part of this invention no more of it is shown; but, however, it is necessary to 70 use the machine in conjunction with a twister and spooler, in order to cable the strand-wires and coil the cable strand-wires on a suitable spool.

H³ is a lever fulcrumed at H' to upwardly- 75 extending lugs m m of bed B, and arranged longitudinally in the machine with bed B. The movable end H² of said lever is provided with a roller-wrist, J, studded to its side and adapted to traverse the channel c'' of cam-wheel c, 80 for working that end of said lever. This lever H³ is provided with the integral upper portion terminating in the head H, for holding the barb-cutters d² d³. The lever H³ is provided with a barb cutter, h', set in its body 85 about midway between its fulcrum and its working end. When the cam c moves the working end of said lever downward, it will cause cutters d² d³ to shear with cutters d d', set in bed B', and when said lever moves upward it will cause cutter h' to shear with permanent cutter h, set in said bed.

The cutters d d' are adjustably secured to bed B' by means of a suitable cap-plate and set-screws, (shown in Figs. 1 and 2 at a,) and 95 cutter h is adjustably secured to said bed by means of cap-plate a² and suitable set-screws, as shown in said figures. The cutters d² d³ are also adjustably held in cutter-head H by means of suitable cap-plates and set-screws, as shown. 100

F F are a pair of feed-rolls secured on shafts S' S', which are properly boxed in the housings F F'', (see Figs. 1 and 2,) and are rotated intermittently to feed forward the barb-strip 5 V, passing between them, by means of crank-wheel Z of shaft S, through the medium of pitman P, lever P', ratchet-wheel R, and pawl P.

On bed B', and immediately in front of and between feed-rolls F F', is located a guide, G, 10 held by a suitable cap-plate, which guides the barb-strip V from said rolls to and between the several cutters, and between the strand-wires W W', as shown in Figs. 1, 2, and by dotted lines in Fig. 3. A pair of barb-strip- 15 adjusting guides, k and n, are set in bed B', as shown in Fig. 1, and are adjusted by means of set-screws to bring them against either edge of the barb-strip to more properly guide and hold it between the said cutters. Guide n is 20 shown in full lines in Fig. 1, and guide k by dotted lines, and their relative position with the barb-strip and cutters is shown in Fig. 3. The strand-wires W W' are arranged to cross the machine over bed B' and between cutters d d' and d' d'', one on either side of the barb-strip 25 V, the lower wire, W', which passes under the barb-strip, being guided by means of the recessed guide t, wh'ch is set between cutters d d', as shown in Fig. 3, and strand-wire W, 30 which passes over the guide-strip, is guided by passing in the channel E' of the reciprocating guide E, as shown in said figure, and also in Fig. 2. This reciprocating guide E rests on cutter d, as shown in Figs. 3 and 5, and is 35 properly held in position by means of a cap-plate, a. (Shown in Figs. 1 and 2.) Said cap-plate is provided with a slot, a', immediately over guide E, through which a stud, a', of said guide passes. Said guide E is reciprocated 40 by means of the lever L, fulcrumed at y, one end of which lever connects with said stud a', and its opposite end is provided with a wrist-roller to operate in the waved cam-channel c' of cam e. Said guide E is timed so as to move 45 forward to separate the strand-wires W W' at the instant the barb-strip is fed forward between them, so it will be certain to enter between them; and it recedes after the barb-strip is fed in and the barb is formed by the 50 cutters, so that the strand-wires may close upon the barb to hold it in, as shown in Fig. 5.

The reciprocating guide E is shown in Fig. 3 as having two channels, E'. It is so formed that when one channel is worn out it may be 55 reversed and the other one used. The strand-wires W W' pass from said guide to a twister and spooler, a portion of which is shown at T, Fig. 1, by means of which they are cabled together to grasp and hold the barbs as they 60 are formed. When cutters d d' descend, they will, in conjunction with cutters d d', cut and form the two downwardly-extending prods of the barb, beginning to shear at their point, and bend them down to the proper angle. The 65 forward upper prod will be bent upward by means of its heel resting on shoulder g of cutter d', the rear upper prod having been cut

and formed in advance by the previous upward move of the lower cutter, h', in conjunction with stationary cutter h. Thus the rear 70 upper prod of a next succeeding barb is being cut and bent upward when cutter h' ascends, and the next downward move of cutters d d', in conjunction with cutters d d', cut and form the remaining prods by cutting on the dotted 75 lines shown in Fig. 4, and each downward stroke of cutters d d' finishes a barb and leaves it between the strand-wires, as shown in Fig. 7.

I claim—

1. In the wire-barbing machine shown and 80 described, the cutters d, d', d'', d'', h, and h', arranged in combination with each other and with bed B' and lever H', and means for operating the lever, whereby at each descent of cutters d d' three prods of a barb are cut and 85 formed and a barb severed from the barbing-strip and seated between a pair of cabling strand-wires, and at each ascent of said lever-cutter h' it, in conjunction with stationary cutter h, cuts and forms the rear upper prod 90 of the next succeeding barb, substantially as set forth.

2. In the wire-barbing machine shown and 95 described, the combination of bed B, secondary bed B', having the several cutters, formers, and guides described, lever H', having the several cutters and formers described, cam e, having the cam-channel c', shaft S, gear-wheel D on said shaft, gear-wheel A of a twister-yoke, and the barb-strip feed mechanism 100 shown and described, as and for the purpose set forth.

3. In the wire-barbing machine shown and 105 described, the cam e, having the cam-channel c'' and the waved cam-channel c', in combination with the levers H' and L, said cam-channel c'' being so formed as to receive roller-wrist J of lever H' and operate said lever, so that its several barb-cutters will shear with the several cutters of bed B', and said annular 110 cam-channel c' being so formed as to receive the roller x of lever L, to operate said lever to reciprocate guide E, in the manner substantially as and for the purpose set forth.

4. In the wire-barbing machine shown and 115 described, in combination with beds B and B', the lever H', having adjustably secured therein the barb-cutters d, d', and h', stationary barb-cutters d, d', and h, guide t, reciprocating guide E, having the channel E' and 120 stud a', barb-strip guides n and k, cam e, having the cam-channels c' and c'', and the barb-strip feed mechanism, all adapted to operate as and for the purpose set forth.

5. In the wire-barbing machine shown and 125 described, the combination of bed B, secondary bed B', arranged to support its several cutters, formers, and guides, as set forth, lever H', arranged to support its several cutters and formers, as described, cam e, lever 130 L, shaft S, gear-wheel D of said shaft, gear-wheel A of the twister-yoke, and the barb-strip feeding mechanism shown and described, whereby the power applied to gear-wheel A

by means of a twister-yoke will operate the several parts of the machine to automatically cut, form, and seat between a pair of cabling strand-wires a four-pointed flat metal barb, in 5 the manner substantially as set forth.

6. In the wire-barbing machine shown and described, the secondary bed B', having the cutters d, d', and h, barb-strip-adjusting guides n and k, stationary strand-wire guide t, and 10 reciprocating strand-wire guide E, arranged substantially as set forth, in combination with lever H³, having the cutters d², d³, and h', ar-

ranged as set forth, and the means, substantially as shown and described, for operating said lever and for feeding forward the barb- 15 strip, for the purpose specified.

7. In the wire-barbing machine described, the guide T, arranged to reciprocate in the manner substantially as described, and for the purpose set forth.

ALBERT J. BATES.
